UNITED STATES PATENT OFFICE.

JAMES MARSDEN, OF WIGAN, ENGLAND.

DESIGN FOR A DIE-PLATE.

SPECIFICATION forming part of Design No. 30,989, dated June 13, 1899.

Application filed May 19, 1899. Serial No. 717,502. Term of patent 14 years.

To all whom it may concern:

Be it known that I, JAMES MARSDEN, a subject of the Queen of Great Britain, residing at Wigan, in the county of Lancaster, England, 5 have invented and produced a new and original Design for Die-Plates, of which the following is a specification, reference being had to the accompanying drawings, forming part thereof.

10 In said drawings, Figure 1 is a plan view of a die-plate, showing my new design. Fig. 2 is an edge elevation of the same. Fig. 3 is a sectional view on line 3 3, Fig. 1.

15 As shown in the drawings, the leading or material feature of my design consists of a

circular die-plate A, formed with a central opening B, concentric depressions C D, and a circular series of perforations a a' a'' in the outer rim of the die-plate, said perforations being of graduated sizes arranged as shown. 20

Having thus described my invention, what I claim as new, and desire to secure by Letters Patent, is—

The design for a die-plate as herein shown and described.

JAS. MARSDEN.
